LUNG IMMOBILIZER

Jan Leyenaar, Lexington, Mass., assignor to J. H. Emerson Company, Cambridge, Mass., a corporation of Massachusetts

Application December 4, 1947; Serial No. 789,597

7 Claims. (Cl. 128—30)

1

This invention relates to an apparatus for the treatment of pulmonary tuberculosis which periodically forces gas into and removes gas from the patient's lungs and which maintains his chest and lungs substantially motionless during such operation.

The most successful prior art type of such apparatus includes a chamber to enclose the patient's body from his feet to his neck, a chamber to enclose his head, a partition which separates these chambers and which is provided with an opening to accommodate the patient's neck, a slide for varying the size of the opening and either a centrifugal type pump or two impeller type pumps which communicate with the head enclosing chamber and which alternately create periods of positive and negative pressures therein. By suitably adjusting the effective size of the opening in the partition (by manipulation of the slide) the respective amounts of the pressure exerted on the opposite sides of the patient's thorax and diaphragm at any instant are equalized by delaying or reducing in degree the amount of the pressure in the body enclosing chamber compared to the amount of the pressure in the head enclosing chamber as the positive and negative pressures are being built up or diminished, thereby to compensate for the resistance of the respiratory passageway to the gas as it passes inwardly or outwardly therethrough.

It has been found that if the pressure within the body enclosing chamber is thus maintained at an amount which is approximately 5 cm. of water less than the amount of the pressure in the head enclosing chamber during each period from maximum negative to maximum positive pressures and approximately 5 cm. of water greater than the amount of the pressure in the head enclosing chamber during each period from maximum positive to maximum negative pressures, the respective pressures on the outer and inner surfaces of the thorax and diaphragm are substantially the same and the chest wall and the lungs are accordingly maintained substantially immobile while gas is periodically forced into and withdrawn from the lungs. A more complete description of the use of this prior art machine may be found in an article by Dr. Alvan L. Barach in the November-December 1946 issue of the Journal of the American College of Chest Physicians, volume XII, number 6.

This prior art machine had several objectionable features. One objection is that with the use of an impeller type or a centrifugal type pump for creating periodic periods of positive and

negative pressures the air transmitted to the head enclosing chamber is heated substantially, and is turbulent, and for these reasons is uncomfortable to a patient in the apparatus; furthermore each type of apparatus is noisy in operation. Another objection, which is particularly true in the use of an impeller type pump or pumps, is that a pulsation is created in the air stream each time the impeller completes a revolution, thus creating a series of vibrations or pulsations of the air in the head enclosing chamber which are undesirable from a standpoint of noise and also from the standpoint of the effectiveness of the apparatus to maintain the walls of the chest substantially motionless. A further objection is that with both of said types of pumps it has been impossible to produce a uniform and progressive increase in the amount of positive pressure within the head enclosing chamber until it reaches the predetermined maximum amount, then a uniform and progressive decrease in said positive pressure until it returns to atmospheric, then a uniform and progressive increase in the amount of negative pressure in the head enclosing chamber until it reaches the predetermined maximum and then a uniform and progressive decrease in said negative pressure until it returns to atmospheric, i. e. it has been impossible to faithfully reproduce the uniform curve for the variations in pressure within the head enclosing chamber which is desirable. A further objection is that the impeller type or the centrifugal type pressure varying apparatus is expensive and is difficult to control in operation.

35 It is the object of this invention to provide an

improved pressure creating mechanism in combination with a lung immobilizer which is simple

and economical in construction and operation

and which functions to provide a uniform pres-

40 sure varying curve.

A further object is to provide such a lung im-

mobilizer wherein substantially less heat and sub-

stantially no turbulence or pulsations are created

45 by the pressure varying mechanism and trans-

mitted to the head enclosure of the apparatus

and which is also quiet in operation.

A further object is to provide such a lung im-

mobilizer wherein the maximum amounts of the

positive and negative pressures may be readily

50 controlled and wherein the shape of the curve

created by the pressures within the head enclos-

ing chamber may be controlled as desired.

A further object is to provide a lung immobilizer

having a pressure creating mechanism of the re-

ciprocating type wherein both the head enclos-

ing chamber and the pressure creating mechanism are automatically supplied with fresh air from the atmosphere prior to the end of each period of negative pressure and without interfering with the uniformity of the pressure varying curve thereby to insure a supply of substantially fresh air to be forced into the patient's lungs during each period of positive pressure.

A further object is to provide such a lung immobilizer with a pressure creating mechanism of the reciprocating type which is free from pressure actuated spring loaded valves, thereby greatly reducing the size of the pressure varying mechanism and reducing the amount of power required for its operation.

A further object is to provide a lung immobilizer which is simple and economical in construction and operation.

Other objects relate to the construction and to the mode of operation and will be apparent from a consideration of the following description and the accompanying drawings which exemplify three embodiments of the invention chosen for the purposes of illustration.

In the drawings:

Fig. 1 is a side elevation of a lung immobilizer embodying my invention with the body enclosing chamber slightly separated preparatory to the insertion of a patient;

Fig. 2 is an enlarged elevation looking from left to right at Fig. 1 of the separating partition removed;

Fig. 3 is an enlarged section taken on the line 3-3 of Fig. 1;

Fig. 4 is an enlarged side elevation of the pressure varying mechanism looking at the mechanism from the same side as it is shown in Fig. 1 but with the front wall of the cabinet removed and two side walls shown in vertical section;

Fig. 5 is a section taken on the line 5-5 of Fig. 4 but with the motor removed except for its drive pulley;

Fig. 6 is an enlarged section on the line 6-6 of Fig. 4;

Fig. 7 is an enlarged section on the line 7-7 of Fig. 5;

Fig. 8 is an enlarged plan of an atmospheric pressure varying cam removed;

Fig. 9 is a diagrammatic view illustrating pressure varying curves produced by the apparatus;

Fig. 10 is a side elevation partially in vertical section showing another embodiment of pressure varying apparatus of this invention; and

Fig. 11 is a side elevation, partially in vertical section, showing still another embodiment of the invention.

The head enclosing chamber as illustrated consists of a dome-shaped member 10, which may be made of any rigid material, for example a transparent plastic, and the body enclosing chamber consists of the two complementary casing members 11 and 12 also of rigid material, for example metal. When the complementary casing members are moved to end abutting relationship, the flange 13 of the shorter casing member 11 is held in air-tight or sealed relationship against the flange 14 of the longer casing member 12 by the clamp 15 by rotating the clamp about its pivotal connection 16 so that its inner curved face engages the side of the pin 11A, this pin being secured to the casing member 11. A similar clamp and pin are provided on the opposite side of the machine.

The casing member 11 and the head enclosing chamber 10 are supported from the floor by a pair

of vertical legs 17, one located at each side of the casing member, and by a pair of casters 18 adapted to roll along the floor as the casing member 11 is moved toward or away from the casing member 12.

The casing member 12 is supported by two pairs of legs 19 and 20, one pair being located at the front end of the casing and the other pair at the foot end thereof and each leg terminating in a caster 21 which rests upon the floor.

A bed 23 has its head end secured to the casing member 11 and its foot end supported for sliding movement longitudinally of the interior of the casing member 12, for example by a pair of casters (not shown) which roll upon longitudinally extending tracks (not shown) secured to the inside face of the wall of the casing 12. Thus as the casing member 11 is moved outwardly from or inwardly toward the casing member 12, the bed 23 moves with the casing member 11 and is correspondingly withdrawn from or inserted in the casing.

As shown in Fig. 3, the casing member 11 is provided with a flange 25 and the dome 10 is provided with a corresponding flange 26. The partition member 28, made of rigid material, for example a transparent plastic, is secured between the flanges 25 and 26 by bolts 29 which pass through perforations 30 (Fig. 2) in the partition member 28 and corresponding perforations in the flanges 25 and 26 and which are secured to the ring washer 34. Rings of compressible material 31, 32 and 33, for example rubber, are interposed between the partition 28, the flanges 25 and 26 and the ring washer 34 to insure an air-tight seal.

The partition 28 is provided with an opening 35 which is large enough to permit the passage therethrough of the patient's head. A head rest 36 is secured to the outer face of the partition 28 by means of brackets 37 and screws 38 which pass through registering perforations (not shown) provided in the brackets and the partition.

A slide 41 is mounted for vertical sliding movement in the two ways 42 which are provided by the inner face of the partition member 28 and two vertical channels formed in the adjacent sides of the members 44, said members being secured to the partition member 28 by screws 45.

The lower end of the rod 47 is detachably secured to the bracket 48 which is secured to the face of the slide 41 by screws 49. The rod 47 extends upwardly through a perforation in the casing member 11 and it is provided with a head 50 (Fig. 1). A collar 51 surrounds the rod 50 and is detachably secured to it by the thumb screw 52. Another collar 53 surrounds the rod 47 and is detachably secured to it by the thumb screw 54. By raising or lowering the rod 47 corresponding movement is imparted to the slide 41 and its lower end accordingly functions to enlarge or reduce the effective size of the opening 35 so that the space between the edges of this opening and the neck of the patient may be varied to correspondingly delay or reduce the amount of pressure transmitted from the interior of the head enclosing chamber 10 through this space to the interior of the body enclosing chamber. The collars 51 and 53 serve detachably to retain the rod 47 at any desired elevation.

A porthole 60 is provided to permit the observation of the patient's chest.

A water manometer indicated generally by the arrow 61 consists of the usual U-tube manometer member (not shown), one leg of which is connected by the flexible tube 62 and the rigid tube 63

with the head enclosing chamber 10 and the other end of which is connected by the flexible tube 84 and the rigid tube 65 to the interior of the body enclosing chamber. This manometer indicates at all times the difference in the amounts of the pressures within the head enclosing chamber 10 and the body enclosing chamber, and, by observing this manometer the required adjustment of the slide 41 may be made. The pressure gauge 68 indicates the amount of pressure in the body enclosing chamber.

The pressure creating mechanism of Figs. 1 to 8 inclusive comprises a cabinet 70 supported by four casters 71. The cabinet comprises a bottom wall 72, top frame members 73 and side walls 74, 75, 76 and 77. On the top of the cabinet an open ended cylinder 80 is supported, the upper end being closed by a cover 81. The piston 82 is mounted for reciprocating movement longitudinally of the cylinder 80, thereby to create in the top of the cylinder positive pressure on the upward stroke and negative pressure on the downward stroke. The interior of the cylinder 80 is connected with the interior of the head enclosing chamber 10 by the rigid tubes 84, 85, the longitudinally flexible tube 86, and the rigid tubes 87, 88, the flexible tube 86 detachably connecting the adjacent ends of the tubes 85 and 87. The other end of the tube 87 is connected to the adjacent end of the tube 88 automatically when flange 13 of the casing member 11 is closed against the face of the flange 14 of the casing member 12 by the clamp 15 and the pin 11A, an air-tight connection being effected by the abutting relationship between the adjacent ends of the tubes 87 and 88 when the clamps 15 are closed, and the ends of these tubes are provided with rings of resilient material to insure an air-tight connection. The interior of the tube 88 communicates with the interior of the head enclosing chamber 10 through the opening 90 which is provided in the partition member 28. The tube 88 may be secured to the partition member 28 by bolts (not shown) which extend through the perforations 91 and registering perforations on a flange (not shown) of the tube.

A horizontal drive shaft 95 (Figs. 4 and 5) mounted in suitable bearings is continuously rotated about its longitudinal axis by the motor 94 which is driven from any suitable source of electric current. The split pulley 96 is keyed to the shaft 97 and the shaft 97 is operatively connected to the drive shaft 95 by suitable gearing (not shown). The motor pulley 98 is operatively connected to the split pulley 97 by the drive belt 99.

The motor is mounted upon a pair of horizontal rods 100 for sliding movement toward or away from the shaft 97. Such sliding movement is effected by rotation of the handle 101 which is secured to the horizontal rod 102 located between the rods 100 and having an exteriorly threaded portion (not shown), the threads of which engage an interiorly threaded passage (not shown) provided in the vertical flange of one of the motor supports 103.

Rotation of the handle 101 causes the motor to be moved longitudinally along the rods 100 towards or away from the axis of the shaft 97 and the operative portion of the belt 99 acting upon the split pulley 96 thereby moves farther away from or closer to the axis of the shaft 97 so that the speed of rotation of the shaft 95

and the corresponding speed of rotation of the drive shaft 95 thereby may be varied.

Secured to the piston 82 (Fig. 5) at the center thereof is a substantially vertical shaft 110. Secured to the drive shaft 95 is a crank arm 111. A connecting rod 112 has its lower end pivotally secured to the crank pin 113 and its upper end pivotally secured to the lower end of the shaft 110 by means of a cross rod 115.

A guide member is formed by the pair of arms 116 and the pair of rods 117. Each of the arms 116 has one end welded to the rod 110 and the opposite end pivotally secured to the ends of the arms 117 by a cross rod 118 (Fig. 4). The other end of each of the rods 117 is pivotally secured to a bracket member 120 which is secured to the cabinet 70. The tension spring 122 has one end anchored to the connecting rod 112 and the other end anchored to the cross rod 118. This guide member formed by the rods 116-117 and the spring 122 functions to maintain the shaft 110 in substantially vertical position as it is reciprocated upwardly and downwardly by rotation of the crank arm 111 by the drive shaft 95, thereby maintaining an air-tight fit between the periphery of the piston 82 and the inner wall of the cylinder 80. On each revolution of the drive shaft 95, the piston 82 is caused to be reciprocated longitudinally of the cylinder 80 a complete stroke, and the interval of time required to complete such reciprocation may be varied by moving the motor 94 toward or away from the axis of the shaft 97.

The tube 84 extends downwardly below its junction with the tube 85 and its lower end is provided with a flange 125 (Figs. 4, 5 and 6). A tube 127 extends from the lower end of the tube 84 downwardly and thence transversely of the cabinet with its outer end passing through the cabinet wall 74 and freely communicating with the atmosphere. Its end which is adjacent to the lower end of the tube 84 is provided with a flange 128 which is held in abutment with the flange 125 by bolts 129 (Fig. 6).

A valve seat 130 is detachably secured within the lower end of the tube 84 by the exteriorly threaded portion thereof which interengages with the interiorly threaded ring 131 secured to the interior of the tube 84. The valve member 135 is secured to the rod 136 and this valve is normally held in closed position by the compression spring 137, the lower end of which rests upon the member 138 and the upper end of which engages the adjacent face of the valve.

The cam 140 (Figs. 5 and 8) is detachably secured to the drive shaft 95. The follower supporting rod 141 is pivotally secured to the support 142, the lower end of which is secured to the bottom cabinet member 72. One end of the follower supporting rod 141 is pivotally secured to the lower end of the rod 143 (Fig. 5) and the follower 144 is pivotally supported between the bifurcated portion of the follower supporting rod 141. The turnbuckle 146 adjustably connects the lower end of the rod 136 and the upper end of the rod 143, this turnbuckle and these two rods being thus constructed so that the distance separating the adjacent ends of these rods may be varied by turning the turnbuckle thus adjusting the length of these two rods as represented by the distance between their outer ends.

Upon rotation of the drive shaft 95 the cam 140 is correspondingly rotated. The cam 140 is so contoured that as it is rotated in the direction

of the arrow of Fig. 8; (i) when the follower 144 is in engagement with the portions *ab* and *cd* of the cam the valve 135 is maintained, seated or closed by the spring 137, thereby closing all communication between the interior of the tube 84 and the atmosphere through this valve; (ii) when the follower is in engagement with the portions *ef* and *gh* of the cam the valve 135 is fully opened by rotation of the follower supporting rod 141 about its pivotal connection, thereby compressing the spring 137 and maintaining free communication between the interior of the tube 84 and the atmosphere through the tube 127; (iii) when the portions *bg* and *cf* of the cam are in engagement with the follower the valve is progressively opened; and (iv) when the portions *hd* and *ea* are in engagement with the follower the valve is progressively closed.

Referring to Fig. 7, the tube 127 is lined with felt 150 and this felt lining is faced with wire screening 151 to deaden sounds transmitted through the tube.

A secondary atmospheric conduit 165 extends between the conduit 127 and the junction of the conduits 84 and 85. This secondary conduit 165 is provided with a valve 166 which is operative to control the effective size of this secondary conduit.

Operation of the apparatus of Figs. 1 to 8

In operation of the embodiment of Figs. 1 to 8 inclusive, the patient is inserted in the patient enclosing chamber by sliding the casing portion 11 away from the casing portion 12 far enough to permit the patient to be placed upon the bed 23. The patient's head is then inserted through the opening 35 in the partition 28 and placed upon a pillow located on the head rest 36. The casing portion 11 is then slid toward the casing portion 12 and these casing sections are sealed in end abutting relationship by rotating the clamps 15 into contact with the pins 11A. In this condition, the patient's body up to his neck is enclosed in a substantially air-tight chamber formed by the casing members 11 and 12 and his head is supported on the head rest 36 within the substantially air-tight head enclosing chamber formed by the dome 10, and a conduit affording communication between the head enclosing and the body enclosing chambers is provided by the space between the patient's neck and the lower edge of the slide 41 and the lower edge of the opening 35 respectively.

Closure of the clamps 15 also causes an abutting relationship between the adjacent ends of the tubes 88 and 87 and thereby provides free communication between the interior of the head enclosing chamber 10 and the interior of the operative end of the cylinder 80 through the tubes 88, 87, 86, 85 and 84.

The motor 96 is then started and this causes continuous rotation of the drive shaft 95 by means of the belt 99, split pulley 96 and the shaft 97. Rotation of the drive shaft 95 causes corresponding rotation of the cam 140 and movement of the crank arm 111. Movement of the crank arm 111 causes longitudinal movement of the connecting rod 112 which causes vertical reciprocation of the shaft 110 and piston 82, the guide rods 116-117 maintaining movement of the shaft 110 substantially in a vertical direction. On the upstroke of the piston progressively increasing positive pressure is created in the upper portion of the cylinder 80 and on the down stroke of the piston progressively increasing negative pressure is created

therein and these pressures are transmitted through the continuously open tubes 84, 85, 86, 87 and 88 to the head enclosing chamber 10 and thence to the patient's lungs through his nose and mouth. These pressures are also transmitted to the body enclosing chamber through the opening in the partition 28 and the size of this opening is adjusted by longitudinal movement of the rod 47 and corresponding sliding movement of the slide 41 so that on the positive pressure stroke, for example, the amount of the pressure in the body enclosing chamber is substantially 5 cm. of water less than the amount of the pressure in the head enclosing chamber at substantially any given instant. For example, during the instant when the positive pressure in the head enclosing chamber is 45 mm. of mercury, the positive pressure in the body enclosing chamber is 5 cm. of water less than 45 mm. of mercury. As appears more clearly from Fig. 9 the pressures in the head and body enclosing chambers are equal shortly after the maximum positive and negative pressures in the head enclosing chamber. This 5 cm. adjustment is accomplished by observing the manometer 61 while adjusting the slide 41.

The cam 140 is arranged (i) to open the valve 135 when the piston 82 has completed about five-sixths of its upward stroke, (ii) to close the valve 135 when the piston has completed about one-sixth of its downward stroke, (iii) to re-open the valve 135 when the piston has completed approximately five-sixths of its downward stroke and (iv) to re-close the valve when the piston has completed approximately one-sixth of its upward stroke. Thus the head enclosing chamber 10 and the interior of the cylinder 80 are in communication with the air of the atmosphere during approximately one-third of the length of each upward movement and one-third the length of each downward movement of the piston, and the valve is completely closed during about two-thirds of the length of each upward movement and two-thirds of the length of each downward movement of the piston.

Stated in terms of elapsed time the valve 135 is in partially open and in fully open position approximately one-half of the time required for each stroke and in fully closed position approximately one-half of the time required for each stroke as clearly appears from Fig. 9 of the drawings wherein (i) the line *xy* represents atmospheric pressure, (ii) the full line 1-2-3-4-5-6-7 represents pressures in the head enclosing chamber, and (iii) the dot dash line 1'-2'-3'-

4'-5'-6'-7' represents pressures in the body enclosing chamber. Thus the point marked 1 in the curve represents the point where the valve closes on the down stroke of the piston, the point marked 2 represents the point where the valve commences to open on the down stroke of the piston, the point marked 3 represents the point where the valve closes on the upstroke of the piston, the point marked 4 represents the point where the valve commences to open on the up-

stroke of the piston and the point marked 5 represents the point where the valve closes on the next down stroke of the piston. The points 6 and 7 represent valve openings and closings in the next stroke of the piston corresponding respectively to the points 2 and 3 on the first stroke. This chart of Fig. 9 is plotted in elapsed time, the area 3-4-5-3 being positive pressure and the areas 1-2-3-1 and 5-6-7-5 being negative pressures in the head enclosing chamber,

75 and the area 3'-4'-5'-3' being positive pres-

sure and the areas 1'-2'-3'-1' and 5'-6'-7'-5' being negative pressures in the body enclosing chamber.

As shown the negative pressure created by the downward stroke of the piston is gradually relieved beginning at the point 2 until the pressure in the cylinder 80 and in the head enclosing chamber has been increased to atmospheric at the point 3 and the valve then completely closes, the piston then being at approximately one-sixth of the distance upon its upward stroke. This action from the point 2 to the point 3 not only gradually and progressively increases the pressure in the cylinder 80 and the head end 10 of the chamber from the maximum negative pressure to atmospheric but it also supplies fresh air to the head enclosing chamber and to the interior of the cylinder 80, the fresh air being admitted through the tubes 127, 84, 85, 86, 87 and 88. A gradual and progressive decrease from maximum positive pressure to atmospheric is accomplished by opening and closing the valve from the point 4 to the point 5 and gases are exhausted to the atmosphere during this period. The resultant pressure curve shown in Fig. 9 is a smooth curve.

Normally the apparatus is adjusted to create approximately 25 cycles of positive and negative pressure per minute but the number of cycles per minute may be varied by moving the motor toward or away from the axis of the shaft 97, such movement being accomplished by rotation of the handle 101.

The maximum amount of the positive pressure within the head enclosing chamber on each cycle is normally limited to from 40 to 55 mm. of mercury, and the maximum amount of negative pressure in the head enclosing chamber is also normally limited to from 45 to 55 mm. of mercury. The maximum positive pressures may be controlled by means of the valve 166, thereby in effect creating a controlled leak between the atmosphere and the interior of the head enclosing chamber. This adjustment correspondingly controls the maximum amount of negative pressure created in the head enclosing chamber on each stroke of the piston.

The pressure varying curve of Fig. 9 may be changed as desired by varying the contour of the cam 140 but in the preferred embodiment of this invention the valve is fully opened prior to the end of the downward or negative pressure stroke of the piston which is also prior to the beginning of the upward or positive pressure stroke of the piston thereby (i) to prevent a sudden change from maximum negative pressure to atmospheric pressure at the end of the downward stroke and at the beginning of the upward stroke of the piston and also (ii) to permit sufficient time for the admission of an adequate supply of fresh air prior to the creation of each phase of positive pressure.

The embodiment of Fig. 10

The device illustrated in Fig. 10 is constructed like that of Figs. 1 to 8 except that a flexible diaphragm 170 is substituted for the piston 82. The diaphragm may be made of leather or other substantially air-tight flexible fabric. The cylinder 80A is provided with a flange 80B and the edge of the diaphragm is clamped between this flange and the top frame members 73A of the cabinet. The diaphragm is secured to the end of the shaft 110 by means of the metallic discs 171 and 172 which engage opposite faces of the

diaphragm. The cover 81A is secured across the upper end of the cylinder 80A. The tubes 84, 165 and 85 are of the same construction as the corresponding tubes of the embodiment of Figs. 1 to 8 inclusive, as are all other parts of the apparatus.

In operation the diaphragm is moved between the two dot-dash positions during reciprocation of the shaft 110, positive pressure being created during upward movement and negative pressure during downward movement. The operation of the valve 135 and the adjustment of all controls are exactly the same in this embodiment as in the embodiment of Figs. 1 to 8 inclusive.

The embodiment of Fig. 11

In the apparatus of Fig. 11 perforations 180 are provided near the lower end of the cylinder 80, and a valve 182 is mounted in a passage formed through the cover 81. The valve housing 183 is detachably secured to the cover and the valve rod 184 is slidably received by this housing. The valve 182 is secured to the rod 184. The compression spring 185 has one end seated on the valve 182 and the other end seated on the valve housing 183 so that it normally holds the valve seated. Four guide flutes 186 are secured to the valve 182 and they serve to guide the lower end of the rod 184 during vertical sliding movements thereof.

In this apparatus the cam 140, follower 144 and follower supporting member 141 of Figs. 1 to 8 are omitted and the valve 135 permanently obstructs or closes communication between the tubes 84 and 127, but the other parts of the apparatus may be the same as that of Figs. 1 to 8 except as above described.

In operation the piston 110 is reciprocated by the drive shaft 95 between the upper and lower dot-dash positions shown in Fig. 11. As the piston progresses upwardly from the full line position of Fig. 11 it contacts the lower end of the rod 184 and elevates it. This opens the valve 182 and gases are exhausted to the atmosphere. The valve is maintained open until the piston has returned to the full line position at which point it is fully closed by the spring 185. This valve remains closed as the piston is moved downwardly and upwardly until it reaches the full line position again on its upward stroke.

As the piston passes downwardly from the intermediate dot-dash position, communication is opened between the atmosphere and the interior of the cylinder 80 as the edge of the piston passes below the upper edges of the perforations 180 and such communication is maintained to admit fresh air until, on the upward stroke, the edge of the piston is elevated to a position above the upper edges of the perforations. The lower dot-dash position of the piston represents the bottom of the stroke. The length of the lower portion of the rod 184 and the elevation of the perforations 180 controls the opening of the atmospheric communication prior to the negative and prior to the positive pressure strokes respectively.

The maximum amounts of the pressures may be controlled by the valve 166 (Figs. 4 and 5) and the speed reciprocation of the piston may be controlled by the handle 101 (Fig. 4).

From the foregoing it will be apparent that the apparatus of this invention provides an improved immobilizer which is simple and economical in construction, which provides a uniform pressure varying curve, in which substantially no heat and

substantially no air vibrations or pulsations are transmitted to the head enclosing portion in which substantially no noise is created in operation, in which both the head enclosing chamber and the pressure creating mechanism are amply supplied with fresh air from the atmosphere prior to the commencement of each period of positive pressure without interfering with the uniformity of the pressure varying curve and in which the maximum amounts of the positive and negative pressures may be controlled as well as the number of pressure varying cycles per minute, and in which the pressure varying mechanism is of the reciprocating type and is free from spring loaded valves so that the size of the pressure varying mechanism and the amount of power required for its operation is small.

While I have shown and described three desirable embodiments of an apparatus embodying my invention, it is to be understood that this disclosure is for the purpose of illustration only and that equivalent forms of the apparatus may be used without departing from the spirit and scope of the invention as set forth in the appended claims.

I claim:

1. In a lung immobilizer having a body-enclosing chamber, a head-enclosing chamber, a partition separating said chambers, a conduit affording communication between said chambers at all times, and mechanism for varying the effective size of said conduit, the improvement comprising a pressure-creating mechanism including a pressure-creating member which is continuously in communication with the head-enclosing chamber, a reciprocating member operative to actuate the pressure-creating member to create a period of negative pressure within the head-enclosing chamber during each movement of the reciprocating member in one direction, an atmospheric conduit operative to afford free communication between the head-enclosing chamber and the air of the atmosphere, a movable member operative to control said free communication between the head-enclosing chamber and the air of the atmosphere through said atmospheric conduit, and means to actuate said movable member to open said communication through the atmospheric conduit prior to the end of each movement of the reciprocating member in a direction to create a period of negative pressure, whereby both the head-enclosing chamber and the pressure-creating mechanism are supplied with air from the atmosphere through said atmospheric conduit prior to the end of each movement of the reciprocating member in a direction to create a period of negative pressure.

2. In a lung immobilizer having a body-enclosing chamber, a head-enclosing chamber, a partition separating said chambers, a conduit affording communication between said chambers at all times, and mechanism for varying the effective size of said conduit, the improvement comprising a pressure-creating mechanism including a pressure-creating member which is continuously in communication with the head-enclosing chamber, a reciprocating member operative to actuate the pressure-creating member to create a period of negative pressure within the head-enclosing chamber during each movement of the reciprocating member in one direction, an atmospheric conduit operative to afford free communication between the head-enclosing chamber and the air of the atmosphere, a movable valve member to

open and close said communication through said atmospheric conduit, a cam to control movement of said valve member, and means to actuate said cam to open said communication through the atmospheric conduit prior to the end of each movement of the reciprocating member in a direction to create a period of negative pressure, whereby both the head-enclosing chamber and the pressure-creating mechanism are supplied with air from the atmosphere prior to the end of each movement of the reciprocating member in a direction to create a period of negative pressure.

3. In a lung immobilizer having a body-enclosing chamber, a head-enclosing chamber, a partition separating said chambers, a conduit affording communication between said chambers at all times, and mechanism for varying the effective size of said conduit, the improvement comprising a pressure-creating mechanism including a pressure-creating member which is continuously in communication with the head-enclosing chamber, a reciprocating member operative to actuate the pressure-creating member to create a period of negative pressure within the head-enclosing chamber during each movement of the reciprocating member in one direction, an atmospheric conduit operative to afford communication between the head-enclosing chamber and the air of the atmosphere, a movable valve member to open and close communication through the atmospheric conduit, a cam to control the movement of said valve member, said cam having a contour such that the valve is opened prior to the end of each movement of the reciprocating member in a direction to create a period of negative pressure and is maintained open for a substantial period, and means to actuate said cam, whereby both the head-enclosing chamber and the pressure-creating mechanism are supplied with air from the atmosphere prior to the end of each movement of the reciprocating member in a direction to create a period of negative pressure.

4. In a lung immobilizer having a body-enclosing chamber, a head-enclosing chamber, a partition separating said chambers, a conduit affording communication between said chambers at all times, and mechanism for varying the effective size of said conduit, the improvement comprising a pressure-creating mechanism including a pressure-creating member which is continuously in communication with the head-enclosing chamber, a reciprocating member operative to actuate the pressure-creating member to create a period of negative pressure within said head-enclosing chamber during each movement thereof in one direction, a primary atmospheric conduit operative to afford free communication between the head-enclosing chamber and the air of the atmosphere, a movable member operative to control said communication between the head-enclosing chamber and the air of the atmosphere through said atmospheric conduit, means to actuate said movable member to open said communication through the atmospheric conduit prior to the end of each movement of the reciprocating member in a direction to create a period of negative pressure, a secondary atmospheric conduit operative to afford communication between the head-enclosing chamber and the air of the atmosphere, and an adjustable member to control the effective size of said secondary conduit, whereby both the head-enclosing cham-

ber and the pressure-creating mechanism are supplied with air from the atmosphere through said primary atmospheric conduit prior to the end of each movement of the reciprocating member in a direction to create a period of negative pressure and the maximum amount of negative pressure in the head-enclosing chamber is controlled by said adjustable member of said secondary atmospheric conduit.

5. In a lung immobilizer having a body-enclosing chamber, a head-enclosing chamber, a partition separating said chambers, a conduit affording communication between said chambers at all times, and mechanism for varying the effective size of said conduit, the improvement comprising a pressure-creating mechanism including a pressure-creating member which is continuously in communication with the head-enclosing chamber, a reciprocating member operative to actuate the pressure-creating member to create a period of negative pressure within said head-enclosing chamber during each movement of the reciprocating member in one direction and a period of positive pressure during each movement thereof in the other direction, movable means operative to control the communication between the head-enclosing chamber and the air of the atmosphere, and means to actuate said movable means prior to the end of each movement of the reciprocating member in a direction to create a period of positive pressure, thereby periodically to open said communication with the air of the atmosphere, whereby both the head-enclosing chamber and the pressure-creating mechanism are supplied with air from the atmosphere prior to the end of each movement of the reciprocating member in a direction to create a period of negative pressure and gases are exhausted therefrom to the atmosphere prior to the end of each movement of the reciprocating member in a direction to create a period of positive pressure.

6. In a lung immobilizer having a body-enclosing chamber, a head-enclosing chamber, a partition separating said chambers, a conduit affording communication between said chambers at all times, and mechanism for varying the effective size of said conduit, the improvement comprising a pressure-creating mechanism including a pressure-creating member which is continuously in communication with the head-enclosing chamber, a reciprocating member operative to actuate the pressure-creating member to create a period of negative pressure within said head-enclosing chamber during each movement of the reciprocating member in one direction and a period of positive pressure therein during each movement of the reciprocating member in the other direction, an atmospheric conduit operative to afford free communication between the head-enclosing chamber and the air of the atmosphere, a movable valve member operative to control the communication between the head-enclosing chamber and the air of the atmosphere through said atmospheric conduit, a cam to control the opening and closing of said valve member, said cam having

a contour such that the valve is opened prior to the end of each movement of the reciprocating member in a direction to create a period of negative pressure and prior to the end of each movement of the reciprocating member in a direction to create a period of positive pressure, and on each occasion is maintained open for a substantial period of time, and means to actuate said cam, whereby both the head-enclosing chamber and the pressure-creating mechanism are supplied with air from the atmosphere prior to the end of each movement of the reciprocating member in a direction to create a period of negative pressure and gases are exhausted therefrom to the atmosphere prior to the end of each movement of the reciprocating member in a direction to create a period of positive pressure.

7. In a lung immobilizer having a body-enclosing chamber, a head-enclosing chamber, a partition separating said chambers, a conduit affording communication between said chambers at all times, and mechanism for varying the effective size of said conduit, the improvement comprising a pressure-creating mechanism including a pressure-creating member which is continuously in communication with the head-enclosing chamber, a reciprocating member operative to actuate the pressure-creating member to create a period of negative pressure within said head-enclosing chamber during each movement of the reciprocating member in one direction and a period of positive pressure during each movement thereof in the other direction, movable means operative to control the communication between the head-enclosing chamber and the air of the atmosphere, and means to actuate said movable means during the time interval between the end of the first five sixths of each movement of the reciprocating member in a direction to create a period of negative pressure and the end of the first one sixth of each movement of the reciprocating member in a direction to create a period of positive pressure, whereby both the head-enclosing chamber and the pressure-creating mechanism are supplied with air from the atmosphere prior to the commencement of the last five sixths of each movement of the reciprocating member in a direction to create a period of positive pressure.

JAN LEYENAAR.
